UNITED STATES PATENT OFFICE.

MAURICE BERKOWITZ, OF NEW YORK, N. Y.

PATCH-ENVELOP MACHINE.

1,161,829.

Specification of Letters Patent. Patented Nov. 30, 1915.

Application filed October 27, 1914. Serial No. 863,795.

To all whom it may concern:

Be it known that I, MAURICE BERKOWITZ, a citizen of the United States, residing in the city, county, and State of New York, have invented certain new and useful Improvements in Patch-Envelop Machines; and I do hereby declare the following to be a full, clear, and exact description of the invention, such as will enable others skilled in the art to which it appertains to make and use the same.

The invention relates to machines for making "transparent window" envelopes having a sight opening covered by a transparent patch, and its object is to provide a machine of simple and easily adjusted parts such as to be capable of producing a better product at an increased rate and with less wastage than the machines now used for the purpose; and such that the machine may be easily adapted to the manufacture of various styles of envelopes differing from one another in the size, shape and location of the patch.

To this end novel gumming mechanism has been devised, of few and simple parts, which can be easily and accurately timed with respect to the other moving elements of the machine, and which acts, in conjunction with a novel arrangement of the patch-hopper, to apply the gum reliably and evenly to the very edge of the outlook opening and to affix the patch at the first, or picker, stage of the machine, that is, while the envelop blank is on the elevator and before it passes into the folding mechanism. Furthermore, the arrangement is such that by replacing the gumming die, its actuating cam, and the patch-hopper, a patch of any desired size may be applied to any selected portion of the face of the envelop.

Referring to the accompanying drawings showing an illustrative embodiment of the invention, and in which the same reference numerals refer to similar parts in the figures: Figure 1 is a front elevational view of the envelop machine. Fig. 2 is an end elevational view thereof. Fig. 3 is a transverse sectional view taken on the line A—B of Fig. 1, and Fig. 4 is a fragmentary longitudinal sectional view on the line C—D of Fig. 2, all of these views showing the parts in the same intermediate position. Figs. 5 and 6 are detail views showing the gum die plunger and the patch-hopper in their extreme positions. Fig. 7 is a detail

sectional view of the means for raising and lowering the die which applies gum around the opening in the blank. Fig. 8 is a side elevational view of the said gumming die, parts being broken away for the sake of clearness. Fig. 9 is a plan view of Fig. 8, part being broken away, and Fig. 10 is a plan view of an envelop blank having the transparent patch applied thereto.

Referring to the drawings, 1 designates the frame of an envelop machine, upon which is mounted an elevator table 2 adapted to support a pile of envelop blanks 3, which is automatically moved upward in the usual manner as the envelopes are transferred from the top of the pile to the creasing and folding mechanism.

Reciprocatingly mounted upon the frame 1 is a vertical plunger 4 carrying at its lower end flap/gumming dies 5 of the usual type. The plunger is reciprocated by any suitable mechanism, as, for example, by a cam 6 secured to the cam shaft 7 and actuating a link 8 which is connected to the plunger 4 by means of a rock shaft 9 and cranks 10 and 11. When the plunger is in its raised or inoperative position, the gumming dies 5 are supplied with gum in the usual manner by means of gumming rolls 12 carried on a horizontally extending frame 13 and adapted to be reciprocated by the links 58—58, 59—59 and shaft 60 actuated by the usual cam mechanism, not shown. Gum is supplied to the gumming rolls 12 by means of a roller 61 rotating in a gum box 62. The parts thus far described form no part of the invention, being parts of the usual envelop machines.

Reciprocatingly mounted in a bracket 14 is a horizontally extending slide 15 carrying at its inner end a gumming die 16, having the configuration of the opening in the envelop blank for applying gum around such opening.

As shown in Fig. 8, shock absorbing means are provided between the die 16 and the slide 15 comprising plungers 17 projecting from recesses 18 formed in the die, and being yieldingly held in engagement with the member 15 by means of springs 19.

Pins 20 carried by the member 15 and extending through elongated slots 21 formed in the die permit movement of the die relatively to the member 15 when the die engages the blank. The member 15 is reciprocated by means of a cam 22 mounted in the

cam shaft 7 and engaging a cam roll 23 carried on a pivoted lever 24 which is connected to the rock shaft 25 by a link 26. The rock shaft 25 is connected to the slide 15 by an arm 27 and a link 28. The cam 22 is so shaped and adjusted that the slide 15 will receive a complete reciprocating movement for each corresponding movement of the plunger 4 and the movement of the parts 5 is preferably so timed that the slide 15 will occupy its innermost position when the plunger 4 is in its uppermost position.

In order that the die 16 may be applied to the envelop blank when the slide 15 is in its 10 innermost position, means are provided for vertically reciprocating the supporting bracket 14, which means consists of a rack 29 secured to the bracket and meshing with a segmental gear 30, secured to a shaft 31, 15 to which shaft a crank 32 is also secured.

Rocking movement is imparted to the 20 crank 32 by means of a link 33, one end of which is secured to the crank and the other end of which carries a cam roller 34 co-operating with a cam 35 secured to the cam shaft 7. The cam 35 is so shaped and adjusted as to cause the die 16 to assume its 25 lowermost position when the slide 15 is in its innermost position, and as the slide 15 returns to its outermost position, to cause the die 16 to be raised from the blank and held in position to engage the die gumming roller 36, in order that the die may receive a fresh 30 supply of gum for each envelop, after which the die will be raised to its uppermost position in which it remains until the slide 15 again occupies its innermost position. Gum 35 is supplied to the gumming roller 36 by means of a roller 63 rotating in an auxiliary 40 gum box 64. This arrangement for applying gum to the die 16 has the advantage (as compared with prior machines in which the gum is applied to the flap-gumming dies and to the die for supplying the patch gum by 45 rollers supplied from a common gum box and replenished only for every alternate envelop,) that a special gum may be used particularly compounded for use with the glazed paper or gelatin of which the patches 50 are made; and the renewal for each envelop followed immediately by the application of the patch, produces the most favorable conditions for the use of the gum, thereby substantially reducing the difficulties which 55 have heretofore attended the gumming of such patches.

Positioned between the flap gumming dies 5 is a hopper 37 in which is carried a pile of 60 transparent patches 38 and a weight or pressing plate 61. The hopper, which is positioned above the envelop blanks and in registry with the openings therein, is supported by rods 39, slidably mounted in guides 40 and 41 carried by the plunger 4. 65 The hopper 37, which is urged to occupy its

lowermost position by springs 42 surrounding the rods 39, and engaging the guide 40 and stops 43 secured to the rods 39, is normally held in its raised or inoperative position, in which position its bottom edge is 70 above the surface of the flap gumming dies 5, by arms 44 secured to a rock-shaft 45, and provided with rollers 46 engaging collars 47 secured to the rods 39.

Rocking motion is given to the shaft 45 75 through crank 48, and link 49 which carries a cam roll 50 engaging a cam 51 secured to the cam shaft 7. The cam 51 is so shaped and adjusted with relation to the cam 6, controlling the movement of the shaft 9, that 80 the dies 5 and the patch hopper 37 will travel downward in unison from their uppermost positions, until the dies 5 engage the envelop blank, after which the dies will be held in engagement with the blank while 85 the hopper 37 is permitted to move down relatively to the dies until the lowermost patch carried by the hopper will be brought into engagement with the gum which has been applied around the opening in the 90 blank by the die 16 as above described. There then occurs a dwell producing a period of contact during which the patch adheres to the gummed edges of the opening. The hopper 37 will then be raised 95 relatively to the dies 5 which are still held in their envelop engaging position. As the hopper is raised the lowermost patch, which will adhere to the gum on the blank, will, of course, be withdrawn from the hopper and 100 will be retained on the blank forming a transparent covering for the opening. After the hopper has been raised to pull the lowermost patch therefrom, the dies 5 and hopper 37 will thereafter be raised in unison, 105 the dies 5 picking the envelop from the pile, and delivering it to the usual creasing and folding mechanism, not shown.

For making envelops provided with openings differing in shape and size from that 110 shown in the drawings, it is only necessary to change the cam 22 to vary the throw of slide 15, to replace the die 16 by one appropriately shaped to correspond to the new form of opening, and to replace the hopper 115 37 by one properly shaped and located to hold and apply the new form of patch.

In addition to the simplicity of the parts, leading to reliability of operation of the 120 gumming mechanism in exact time with the other moving parts, the described machine has the great advantage that the gum is applied about the opening in the envelop blank, and the patch is likewise applied to the blank, during the picker stage while the 125 blank is solidly supported by the elevator or blank support.

What I claim is:

1. In a patch envelop machine, a blank elevator adapted to support a pile of en- 130

- velop blanks having patch openings therein, a flap-gumming die carrier, flap-gumming dies carried thereby, a supplemental gumming device shaped to apply gum about the 5 patch opening in the blank, and actuating mechanism for the said die carrier and the said supplemental gumming device timed to first bring the supplemental gumming device into contact with the top blank of the 10 pile to apply gum about the opening therein and to subsequently bring the flap-gumming dies into contact with the said blank, and a patch-applying device moving with the flap-gumming die carrier to apply a 15 patch to the said blank, whereby the patch opening is closed before the blank is removed from the pile.
2. In a machine for attaching patches to envelop-blanks having patch openings 20 therein, a blank-supporting table and flap-gumming mechanism, means for applying gum about the patch opening in the top envelop-blank while the blank is resting on said table, a patch-hopper carried by the 25 flap-gumming mechanism, and means for actuating the patch-hopper to press a patch on the gummed envelop-blank before the envelop-blank is removed from the blank-supporting table.
3. In a machine for attaching patches to envelop-blanks having patch openings therein, a blank-supporting table and flap-gumming mechanism, means comprising a 30 reciprocating die-carrier and a gumming die 35 removably attached thereto for applying gum about the opening in the envelop-blank while the blank is on the table, a patch-hopper removably attached to the flap-gumming mechanism, and means for actuating 40 the patch-hopper to press a patch on the gummed envelop-blank before the envelop-blank is removed from the blank-supporting table.
4. In a machine for attaching patches to 45 envelop-blanks having patch openings therein, a blank-supporting table, flap-gumming dies arranged to descend upon the top envelop-blank on said table, and a gum-box and gum-rollers for applying gum to the 50 flap-gumming dies, in combination with an auxiliary gum-box, a gumming-die supplied therefrom and shaped to apply gum about the opening in the envelop-blank, mechanism for actuating said die to bring it over 55 and press it upon the envelop blank while the blank is resting on the table, and means

for thereafter applying the patch to the blank before it is removed from the blank supporting table.

5. In a machine for attaching patches to 60 envelop-blanks having patch openings therein, a blank-supporting table, flap-gumming dies arranged to descend upon the top envelop-blank on said table, and a gum-box and gum-rollers for applying gum to the 65 flap-gumming dies, in combination with an auxiliary gum-box, a gum-die shaped to apply gum about the opening in the envelop-blank, mechanism for actuating said die to bring it over and press it upon the 70 envelop-blank while the blank is resting on the said table, and for applying gum to the die from said auxiliary-gum box at each actuation thereof, whereby the gum is renewed 75 on said die for each envelop, and mechanism for applying a patch to the gummed blank before it is removed from the blank-supporting table.

6. Mechanisms for applying patches to 80 envelop-blanks in machines of the character described, comprising reciprocating flap-gumming dies and a reciprocating patch-hopper associated therewith, and mechanism for moving the flap-gumming dies into and out of engagement with an envelop-blank and for moving the patch hopper into engagement with the envelop blank and for moving it out of engagement with the blank during the time that the flap-gumming dies are in engagement therewith. 85

7. In a machine for attaching patches to envelop-blanks having patch openings therein, a blank-supporting table, reciprocating flap-gumming dies, a reciprocating patch-hopper associated with the flap-gumming dies, gumming mechanism for applying gum about the patch-opening in the top envelop-blank on said table and mechanism for moving the flap-gumming dies into and out of engagement with said envelop-blank 90 on the table and for moving the patch-hopper into engagement with the envelop blank and for moving it out of engagement with the blank during the time that the flap-gumming dies are in engagement therewith. 95

In testimony whereof I affix my signature, in presence of two witnesses.

MAURICE BERKOWITZ.
